HEMP BREAKING MACHINE

Adam L. Trumbo, Lancaster, Ky.

Application September 1, 1943, Serial No. 500,851

14 Claims. (Cl. 19—19)

1

This invention relates to a machine for treating hemp.

An object of the invention is the provision of a machine for breaking up the hemp stalks in a successive manner, after which the lint or fiber is separated from the broken stalks and is shaken to prevent the lint from being tangled or injured as it is being carried away from the breaking device.

Another object of the invention is the provision of a machine for crushing and breaking the stalks of hemp at points on the land where the hemp has been harvested, after which the lint fibers or bark from the stalks are separated from each other.

A further object of the invention is the provision of a machine for breaking up hemp stalks and for separating the lint fibers or bark from each other for the ultimate manufacture of rope, twine and calking material for boats and other numerous uses.

A still further object of the invention is the provision of a machine for breaking up the stalks of hemp and for shaking the fibers to prevent tangling of same when the fibers are being carried away from the breaking machine.

Another object of the invention is the provision of a hemp treating machine in which the stalks are broken up successively and progressively into small particles, and in which the fibers are being carried away and properly aligned, the hurds then being carried to a blower where certain of the elements of the stalks are separated from the remaining elements.

Still another object of the invention is the provision of a machine which may be used in various fields where the hemp is grown and which is employed for breaking up the stalks to loosen the lint from the stalks, the hemp being passed through a plurality of rollers with progressively small corrugations until the fibers are discharged upon a conveyor from the breaking device during the travel of the fibers upon the conveyor, after they have left the breaking device, said fibers being received by fingers which are moved directly through the fibers with the fingers being oscillated back and forth to prevent tangling of the fibers.

This invention will be best understood from a consideration of the following detailed description, in view of the accompanying drawings forming a part of the specification; nevertheless, it is to be understood that the invention is not confined to the disclosure, being susceptible of such changes and modifications as define no material

2

departure from the salient features of the invention as expressed in the appended claims.

In the drawings:

Fig. 1 is a side view in elevation of the machine constructed according to the principles of my invention.

Fig. 2 is a transverse vertical section taken along the line of 2—2 of Fig. 1.

Fig. 3 is a fragmentary side view of the machine, showing the oscillating fingers for shaking the fibers as they are passed over the conveyor.

Fig. 4 is a fragmentary side view partly in section of a large detail of the operating means for shaking the fingers.

Fig. 5 is an enlarged transverse vertical section taken along the line of 5—5 of Fig. 3.

Fig. 6 is a fragmentary view partly in section showing an enlarged detail of a finger operating means.

Fig. 7 is an enlarged fragmentary side view of the hemp breaking device.

Fig. 8 is an enlarged fragmentary view in elevation of the opposite side of the hemp breaking machine.

Fig. 9 is a plan view of the hemp treating machine.

Fig. 10 is a fragmentary side view showing the mechanism for operating the shaker device, and

Fig. 11 is a fragmentary section in elevation of the device illustrated in Fig. 10.

Referring more particularly to the drawings, it will be seen that the hemp breaking machine is conveyed by a wheeled carriage which has long beams 10 which are supported by axles 11 and 12 and these axles are in turn supported by the respective wheels 13 and 14. The transverse bars are shown at 15.

Above the framework 10 is a second frame generally designated by the numeral 16, and this framework consists of longitudinal bars 16^a and these bars are supported above the framework by means of posts 18.

Supported upon the framework ends of the longitudinal bars 16^a is a device generally designated by the letter A for breaking up the stalks successively in a manner which will be presently explained. On the remaining portion of the bars 16^a is mounted a device designated by the letter B for straightening out the fibers after they have left the device A. After the fibers are discharged from the breaking device A into the device B they are carried by means of a traveling carrier C which has an upper flight 20 to receive the fibers. The lower flight of said carrier forces

the released pieces of the stalks to the right in Fig. 1 along the top of floor 21, which extends substantially the entire length of the machine so that the lower flight 22 of the traveling conveyor will return the stalks over the top of the floor 21 to a suction blower generally designated by the letter D.

The breaking device A consists of a plurality of pairs of rollers which have their axles extending transversely of the frame and in vertical alignment so that when the material is fed to the first pair of rollers, said rollers will act on the hemp initially after which the hemp is passed between the pairs of successive rollers. Each successive pair of rollers are provided with corrugations at their surfaces and the corrugations progressively decrease in size but also progressively increase in number.

Referring more particularly to Figs. 1, 7 and 8, it will be seen that the first pair of rollers designated by the numerals 25 and 26 have a smooth surface and are respectively carried by axles 27 and 28 and the ends of these axles are respectively carried by bearing blocks 29 and 30.

The bearing block 29 is slidably mounted in a U-shaped frame 31 which also supports the bearing 30, and this frame is secured to the long beam 16^a. A coil spring 32 is located between the bearing block 29 and a presser plate 33, which is carried by a screw 34 threaded into a nut 35 formed at the upper end of the frame 31. A head 36 is adapted to be turned for increasing the pressure on the spring 32, or for relieving the pressure on said spring. The object of the spring is to permit a roller to be raised when too great a mass of material is passed between the rollers 25 and 26.

It will be noted from Figs. 7 and 8 that a yoke 31, together with the associated parts, is located at each side of the machine A for each pair of rollers, the necessary bearings for supporting the various shafts of the rollers being employed.

A main drive shaft 40 is mounted in bearings 41 carried by the beams 16^a. A pulley 42 is secured to the outer end of the shaft and is driven by a motor (not shown) which may be separate from the machine or which may be carried by the frame. This shaft is provided with a pair of gears 43 and 44. The gear 43 meshes with a gear 45, which is secured to a shaft 46, carried by bearings 48 at the outer ends of brackets 49, which project from the beam 16^a.

A gear 50 rigid with one end of a shaft 51 meshes with the gear 44 so that the shaft 51 will be revolved.

The lower roller 26 which has a smooth surface is driven by means of a gear 45^a meshing with a gear 52 which is rigid with one end of the shaft 28 at one side of the machine. The upper roller 25 is driven by a sprocket 53, which is rigid with the shaft 27 and this sprocket in turn is driven by a chain 54 and a sprocket 55 which is secured to the shaft 40.

A pair of corrugated rollers 46 and 57 have the respective shafts 58 and 59 mounted in bearings in the U-shaped brackets 31 on each side of the frame. The shaft 59, and likewise the roller 57, is driven by a gear 60, which in turn is revolved by a gear 61, secured to the shaft 51. The upper roller 56 is driven by the intermeshing of the corrugations of said rollers.

It will be noted that the rollers 62 and 63 are provided with respective shafts 64 and 65 and these shafts are carried by bearings which are likewise mounted in U-shaped brackets 31 at each side of the frame. A gear 66 is secured to the

outer end of the shaft 65 and this gear meshes with a gear 67 which is secured to the shaft 46. In other words, alternate pairs of the vertically disposed rollers are operated by the shaft 51, and associated gears, while the remaining pairs of rollers are revolved by the shaft 46 and associated gears. The upper corrugated rollers in each pair are revolved by the intermeshing corrugations of the pair of rollers. It will be further noted that the rollers 56 and 57 have the least number of corrugations and these corrugations are large. Rollers 62 and 63 have small corrugations but twice the number as do the rollers 56 and 57. Rollers 68 and 69 have double the number of corrugations as do the rollers 62 and 63 and naturally the corrugations are smaller. The remaining rollers of the pairs may have the same number of corrugations as the rollers 68 and 69, or they may have a greater number, thereby providing finer corrugations.

The last pair of rollers 70 and 71 discharge the crushed and broken stalks toward the endless conveyor C and this last pair of rollers is driven by a gear 72, secured to the shaft 51 which meshes with a gear 73, secured to a shaft 74 which in turn is connected to the roller 71.

The conveyor C is driven by sprockets 75 carried by a shaft 76, Figs. 1, 7 and 8. On one end of the shaft is a sprocket wheel 77 upon which is trained a chain 78 which engages a sprocket 79 secured to the shaft 28 that drives the roller 26. The conveyor is supported at its other end by sprockets 80 carried by a shaft 81 which is mounted in bearings 82 at the under face of the parallel bars 16^a. The conveyor consists of spaced parallel bars 83 secured to endless chains of conveyor C mounted on the sprockets 75 and 80. This open conveyor permits the broken stalks and refuse to fall through the conveyor on to the floor 21 but carries the fibers to the outer end of the machine. The conveyor is as wide as the machine and drags on the floor 21 the full width and moves all refuse into a chute 86 and thence into the blower.

A suction blower D is located adjacent chute 86 and is in communication with said chute. A propeller 90 is secured to a shaft 91 upon which is secured a gear 92 meshed with a gear 93, which is secured to a shaft 94. This shaft is driven by a grooved pulley 95, belts 96, a second grooved pulley 97 and the shaft 40. The shaft 94 is mounted in bearings 98 carried by a beam 10 and a cross beam 99.

The fan or blower 90 is mounted in a casing 100 which has a tube 101 extending therefrom for discharging material at one side of the machine.

A device designated by the letter B is located above the remaining portion of the conveyor C which is not covered by the breaking device A. The purpose of the mechanism B is to receive the broken stalks from the last two rollers 70 and 71, and shake the stalks with a transverse oscillating motion as they travel on the conveyor C thus causing openings between the strands of hemp fibers to permit foreign matter to fall through and away from said fibers, thereby cleaning the same. In other words, the mechanism B cooperates with the breaking machine A in a unitary manner in order to separate the fibers from the stalks. The broken pieces of the stalks will fall through the open spaces between the cleats 83 of the conveyor C and will be deposited on the table 21 whence said cleats will push the refuse into the chute 86.

An endless member 105 is located at each side of the frame and these endless members are in the form of chains. They are trained on pairs of sprockets 106 and 107 at the opposite ends of the mechanism. The sprockets 106 are driven by a shaft 108 to which is secured a pulley or sprocket 109 at one side of the machine. A chain or belt 110 drives the sprocket 109 from a sprocket 111 which is secured to a shaft 112. The shaft 112 in turn is driven by a gear 113 meshing with a gear 114. This gear 114 is secured to the shaft 114 at one side of the frame as shown in Figs. 9, 10 and 11.

Referring more particularly to Figs. 1, 3, 4, 5, 6 and 9, it will be seen that a plurality of spaced U-shaped bars 120 are carried by pins 121 projecting laterally inwardly from the chains 105 and at spaced points. Each of the pins 121 is provided with an annular groove 122, Fig. 6, which receives the end of a pin 123 mounted in the side walls 124 and 125 of the U-shaped member 120. The pins revolve in the ends of the U-shaped bars. These bars at the lower flights of the chains 105 ride on angle irons 127 which are secured to the longitudinal bars 128 which provide supports for the chains. The longitudinal bars are secured to posts 129 which are mounted on the beams 16^a. A number of the posts 129 as shown in Fig. 1 are spaced along the beams for supporting various elements. The upper ends of these posts are connected to a pair of longitudinal beams 130 which extend the entire length of the machine. The intermediate portions of the beams 130 are supported by posts 131 and their forward ends which are inclined downwardly, as indicated at 130^a in Fig. 1, are supported on similar posts 132.

A plurality of fingers 133 projects downwardly from the bars 120 and these fingers are pivoted in series as shown at 134 within said bars. In other words these fingers project between the side walls 124 and 125 of the bars 120.

A link 135 connects each row of fingers together so that when one of the fingers 133^a or 133^b is rocked the fingers in each row will be simultaneously rocked. Each link is U-shaped like the bars 120 and these links are cut away as shown at 136 to receive the fingers; pins 137 pivotally connect the fingers to the links.

One finger 133^a in alternate rows of fingers is provided with a head 138 which projects above the upper edge of the respective bars 120, and these bars are cut away as shown at 139 to permit the fingers 133^a to project above and rock within its associated transverse bar 120. A finger 133^b in each of the remaining rows has a head 140 likewise projecting above the supporting bars 120 and the supporting bars are also cut away as shown at 141 to permit rocking of the fingers 133^b. The remaining fingers 133 in each of the last mentioned rows are identical with the fingers 133 of the alternate rows. It will be noted from Figs. 5 and 6 that the heads 138 in the alternate rows are located adjacent chain 105 on the right hand side of the machine while the heads 140 are located adjacent the other chain 105 on the left hand side of the machine.

An oscillating means for the fingers is shown in Figs. 5 and 6 and consists of transverse bars 142 which are connected to the posts 129 above the bars 120 or between the upper and lower flights of the chains 105. Bell-crank 143 and 144 are pivotally mounted as shown at 145 on an enlarged portion 146 of each of the transverse bars 142. The bell-cranks 143 and 144 have re-

spective depending arms 147 and 148 to which are connected the respective channel bars 149 and 150. It will be noted that the channel bars 149 receive the heads 138 of the fingers 133^a in alternate rows, while the channel bars 150 receive the heads 140 of the fingers 133^b in the remaining rows of fingers.

A shaft 151 is provided with a plurality of spaced eccentrics 152 which are mounted in the adjacently disposed circular openings 153 in the horizontal arms of the bell-cranks 143. Thus it will be seen that when the shaft 151 is revolved together with the eccentrics 152, the bell-cranks 143 will be rocked as will be the fingers 133^a in the alternate rows, together with the associated fingers 133.

A shaft 154 is located longitudinally over the conveyor C and adjacent one of the chains 105. This shaft passes through openings 155 in the outer ends of the horizontal arms of the bell cranks 144. In each of the openings of said arms is located an eccentric 156 which is secured to the shaft 154. Thus, when said shaft is revolved the bell-cranks 144 will be rocked for oscillating the arms 148 of said cranks thereby rocking the horizontally disposed U-shaped member which is connected to the lower free ends of the arms 148. Since said U-shaped members receive the heads 140 of the fingers 133^b all of the fingers will be rocked in the remaining rows of fingers in view of the fact that all of the fingers in each row are connected together by the respective links 135.

The shafts 151 and 154 are mounted in bearings 171 and 172. The bearings 171 are supported by transverse bars 185 carried by brackets 173 mounted on the beams 16^a. The bearings 172 are secured to a bar 185 connected to a pair of posts 129.

It will be noted from Figs. 1, 3, 9, 10 and 11, that the shaft 151 is operated by a gear 161 which meshes with a gear 160, secured to a shaft 162, carried by bearing brackets 163^a mounted on the beams 16^a. This shaft in turn is revolved by a sprocket 164, a chain 165 and a sprocket 166, which is secured to shaft 108, Figs. 3 and 9. This shaft in turn is revolved by a sprocket 168, a chain 169 and a sprocket 170, which is secured to the shaft 112, Fig. 10. The shaft 154 is revolved by a gear 175, which meshes with a gear 176, secured to the shaft 162, from which it will be seen that the shafts 154 and 151 are simultaneously rotated.

The shaft 108 is carried by bearings 108^a which are secured to the posts 131 (Fig. 9). The sprockets 107 are secured to a shaft 181 which is mounted in bearings 182 carried by the posts 129 at the rear end of the frame.

A feeding table 186^x is located at the front of the machine to receive the stalks before they reach the rollers 25 and 26. After the stalks pass between these rollers, they are slightly broken, and they are broken to a greater extent when they pass between the successive pairs of toothed rollers beyond the rollers 25 and 26 until they emerge from the rollers 30 and 31, whence the fibers are deposited upon the conveyor C, which is traveling in the direction indicated by the arrow in dotted lines in Fig. 1.

After the fibers are projected on to the conveyor the fingers 133 move downwardly with the chains 105 and over the sprockets 106. As the fingers come downwardly they move through the fibers as they are projected from the rollers 30 and 31 on to the conveyor, and thus these fin-

gers aid in maintaining the fibers in proper positions after they reach the conveyor.

After the fibers are carried along the conveyor the rows of fingers 133 are likewise carried along at the same speed as the fibers. However as the heads 138 and 140 of the alternate sets of fingers enter their respective oscillating runways 149 and 150 the sets of fingers will be rocked simultaneously through their connecting links 135.

Since the timing of the cams 152 and 156 is coordinated with the timing of the movement of the fingers along their definite paths the heads 138 and 140 will be in a position to be received by their respective channel members 149 and 150. The movement of the arms 147 and 148 of the respective bell-cranks 143 and 144 are thus also timed to align the channel members with the respective heads 138 and 140.

While the fibers are passing along the conveyor C under the fingers 133 the fibers will be agitated back and forth so that the fibers will be maintained in proper alinement on the conveyor and thus tangling of the fibers will be prevented. The fibers are then discharged at the end of the conveyor and will be deposited at the rear end of the machine.

When the hemp is fed into the machine and passes through the various corrugations or fluted rollers, the stalks are broken up and a great proportion of the stalks, together with other refuse, falls down from the rollers and through the conveyor C on to the floor 21, whence the broken stalks and refuse are carried to the chute 86 and then into the blower D, whence they are discharged laterally from the machine.

The fibers which have been released from the woody portion of the stalks are then received by the transverse bars 83 on the upper flight 20 of the conveyor. Any pieces of the stalks which have clung to the fibers are loosened by the operation of the fingers 133 and these fingers tend to maintain the fibers in alinement throughout the travel on the upper flight toward the outer end of the machine where the fibers are discharged. When the fibers are discharged, they come out as straight lint and they are twisted in bunches to keep them from tangling, and placed in containers or other suitable receptacles. It would be appreciated, however, that the greater bulk of the stalks is removed after they pass through the fluted rollers of the breaking device A.

I claim:

1. In a hemp machine, a device for treating hemp stalks, a frame, a conveyor extending substantially the length of the frame, means over one end of the conveyor for breaking up the stalks and discharging the same on to the conveyor, a plurality of transversely spaced rows of fingers extending independently of and traveling along the remaining portion of the conveyor and projecting into the hemp carried thereon, means oscillating alternate rows of the fingers in one direction transversely of the conveyor, other means oscillating the remaining intermediate rows of the fingers in the other direction in alternation with the first mentioned rows, and means for moving the rows of fingers along the conveyor.

2. In a hemp machine, a device for treating hemp stalks, a frame, a conveyor extending substantially the length of the frame, means over one end of the conveyor for breaking up the stalks and discharging the same on to the conveyor, a second conveyor located above the first

mentioned conveyor, a plurality of spaced rows of fingers on the second conveyor projecting into the hemp on said first mentioned conveyor, means for causing the fingers to be moved successively into the stalks as they are discharged from the breaking means, and means for rocking the fingers transversely of the conveyors.

3. In a hemp treating machine, a frame, an endless conveyor on the frame, a stalk breaking means over one end of the conveyor and delivering the broken stalks to the conveyor, means driving the conveyor, means over the other end of the conveyor for engaging the fibers when they are delivered to the conveyor, the last mentioned means including a pair of endless driven members, arranged with upper and lower runs, spaced transverse bars carried by the endless members, spaced fingers pivotally mounted on each bar with the lower run of the endless members projecting the fingers into the fibers on the conveyor, means connecting together the fingers of each row on a bar for simultaneous rocking movement of said fingers, one finger in each row having a head above the supporting bar, a longitudinal U-shaped bar rockably mounted and adapted to receive the heads as the supporting bars are moved over the conveyor, and means for rocking the U-shaped bars transversely of the conveyor for rocking the fingers.

4. In a hemp treating machine, a frame, an endless conveyor on the frame, a stalk breaking means over one end of the conveyor and delivering the broken stalks to the conveyor, means driving the conveyor, means over the other end of the conveyor for engaging the fibers when they are delivered to the conveyor, the last mentioned means including a pair of endless driven members, arranged with upper and lower runs, spaced transverse bars carried by the endless members, spaced fingers pivotally mounted on each bar with the lower run of the endless members projecting the fingers into the fibers on the conveyor, means connecting together the fingers of each row on a bar for simultaneous rocking movement of said fingers, one finger in each row having a head, the head in each alternate row being located adjacent one end of the associated supporting bar, the heads in the remaining rows being disposed adjacent the other ends of the associated bars, a pair of spaced U-shaped bars rockably mounted over the supporting bars, the U-shaped bars being so arranged at a side of the frame as to receive the head adjacent said side when the supporting bars are moved over the conveyor and means for shifting the U-shaped bars transversely of the conveyor for rocking the fingers.

5. In a hemp breaking machine, a frame, an endless conveyor on the frame, a stalk breaking means over one end of the conveyor and delivering the broken stalks to the conveyor, means driving the conveyor, means over the other end of the conveyor for engaging the fibers when they are delivered to the conveyor, the last mentioned means including a pair of endless driven members, arranged with upper and lower runs, spaced transverse bars carried by the endless members, spaced fingers pivotally mounted on each bar with the lower run of the endless members projecting the fingers into the fibers on the conveyor, means connecting together the fingers of each row on a bar for simultaneous rocking movement of said fingers, a head projecting from one of the fingers in each of the alternate rows, a head projecting from one of the fingers in each

of the remaining rows, a U-shaped bar positioned to receive the heads in the alternate rows, a second U-shaped bar positioned to receive the heads in the remaining rows as the supporting bars are moved over the conveyor, and means for rocking the U-shaped bars for rocking the rows of fingers projecting into the stalks.

6. A hemp treating machine comprising a breaker for crushing hemp stalks, a conveyor for transporting the latter, endless traveling members at each side of the machine above the conveyor movable in the direction thereof, bars carried at their ends in spaced relation by said members, depending spaced fingers pivotally carried by the bars which successively project into the fibers carried by the conveyor, and means for driving the conveyor and the endless members and means for rocking the fingers in the planes of their respective bars.

7. A hemp treating machine comprising a breaker for crushing hemp stalks, a conveyor for transporting the latter, endless traveling members at each side of the machine above the conveyor movable in the direction thereof, means for driving the conveyor and said members in the same direction, bars supported at their ends in spaced relation on said members, sets of depending fingers pivoted on each of the bars arranged to project into the path of fibers carried by the conveyor as said bars successively approach said conveyor, means operating to oscillate the fingers on alternate bars simultaneously in opposite directions transverse to the conveyor.

8. A hemp treating machine comprising a breaker for crushing stalks, a conveyor for transporting the latter, an endless conveyor superposed thereon having a lower reach movable in the direction of movement of the conveyor and means for synchronously driving said conveyors, transversely extending bars spaced on the reaches of the endless conveyor, sets of depending fingers pivoted on said bars, those on each bar being connected for simultaneous rocking movement, each set having an actuating member, the actuators of adjacent bars being offset from each other and separate means movable laterally and cooperating with said actuators on alternate bars to oscillate the fingers of adjacent bars in opposite directions transversely of the first mentioned conveyor.

9. A hemp treating machine comprising a stalk crusher, two similarly constructed endless conveyors disposed horizontally one above the other each having spaced transversely extending bars, the upper flight of the lower conveyor movable in a direction to convey hemp from the crusher, a platform supporting the lower flight of said conveyor for receiving debris conveyed in the opposite direction by said conveyor to a point of discharge, agitating fingers depending from the bars of the upper conveyor which in the travel of its lower flight enters the body of hemp carried on the bars of the upper flight of the lower conveyor, means for driving the conveyors and means for actuating said fingers to dislodge foreign particles from the hemp during the travel together of the contiguous flights of said conveyors.

10. In a hemp breaking machine a frame, a stalk breaker, a conveyor leading therefrom having transverse bars receiving the stalks and fibers, endless members supported above the conveyor having upper and lower runs carrying transverse bars and means for driving said conveyor and said members, spaced transverse bars carried by the endless members, spaced fingers

pivotedly mounted on each bar with the lower run of the endless members projecting the fingers into the fibers on the conveyor, means connecting together the fingers of each row on a bar for simultaneous rocking movement of said fingers, a head projecting from one of the fingers in each of the alternate rows, a head projecting from one of the fingers in each of the remaining rows, U-shaped bars positioned to receive the heads in the alternate rows as the supporting bars are moved toward the conveyor, and means for rocking one of the U-shaped bars transversely of the conveyor for causing rocking of the fingers in alternate rows, and means rocking the other U-shaped bar for causing rocking of the fingers in the other rows when said fingers are projected into the fibers.

11. In a hemp breaking machine a frame, a stalk breaker, a conveyor leading therefrom having transverse bars receiving the stalks and fibers, endless members supported above the conveyor having upper and lower runs carrying transverse bars and means for driving said conveyor and said members, spaced transverse bars carried by the endless members, spaced fingers pivotally mounted on each bar with the lower run of the endless members projecting the fingers into a position to engage fibers on the conveyor, means connecting together the fingers of each row on a bar for simultaneous rocking movement of said fingers, means causing rocking of the fingers on alternate bars when projected into fiber engaging position transversely of the conveyor and including a projection on one of the fingers in each of the alternate rows of fingers, a rockable means adapted to receive the projection, means oscillating the rockable means, a similar projection on one of the fingers in each of the remaining rows and a rockable means engaging the second mentioned projections for causing oscillation of the remaining rows of fingers.

12. In a hemp treating machine, a frame, a conveyor thereon, means for crushing hemp stalks located above one end of the conveyor, a second conveyor located above the first mentioned conveyor and moving in unison therewith, a plurality of spaced rows of fingers carried on the second conveyor extending transversely thereof and arranged with their free ends adjacent the first mentioned conveyor, and means for rocking said fingers transversely during the longitudinal travel of the conveyors.

13. In a hemp treating machine, a frame, a conveyor thereon, means for crushing hemp stalks arranged to discharge the stalks onto one end of the conveyor, a second conveyor located above and movable longitudinally with the first mentioned conveyor carrying transversely extending bars, rows of fingers depending from the bars arranged to successively engage the crushed stalks as discharged from the crushing means, and to travel with them, and means for rocking said rows of fingers transversely of the first mentioned conveyor during such travel.

14. In a hemp treating machine, a frame, a conveyor thereon, means for crushing hemp stalks arranged to discharge the stalks onto one end of the conveyor, a second conveyor comprising endless members spaced over the edges of the first mentioned conveyor and moving in unison therewith, bars journaled at their ends in spaced relation on said members, pivoted fingers depending from each bar arranged to engage the crushed stalks discharged upon the first mentioned conveyor and to travel with the same and

2,496,570

11

means for rocking said fingers transversely to the direction of movement of the conveyors.

ADAM L. TRUMBO.
